UNITED STATES PATENT OFFICE.

VICTOR E. MEYER, OF LYON'S FARMS, ELIZABETH, NEW JERSEY, ASSIGNOR TO DEBORAH POWERS, ALBERT E. POWERS, AND NATHANIEL B. POWERS, OF LANSINGBURGH, NEW YORK.

DESIGN FOR A FLOOR OIL-CLOTH PATTERN.

Specification forming part of Design No. 5,747, dated April 2, 1872.

To all whom it may concern:

Be it known that I, VICTOR E. MEYER, of Lyon's Farms, city of Elizabeth, county of Union and State of New Jersey, have invented or produced a new and original Design for Floor Oil-Cloths or other fabrics, which is fully shown upon the drawing accompanying this specification, which I hereby declare to be a part thereof; and

What is claimed as my invention, and is desired to be secured by Letters Patent of the United States, is—

The design for floor oil-cloths, as shown on said drawing and herein described.

VICTOR E. MEYER.

Witnesses:

JOHN LIPSEY,
CHAS. T. MEYER.
